To all whom it may concern:

Be it known that I, Lee Barnaby, a citizen of the United States and a resident of the city of Cleveland, county of Cuyahoga, and State of Ohio, have invented a new, original, and ornamental Design for a Table Lamp, of which the following is a specification, reference being had to the accompanying drawing, forming a part hereof.

I claim:

The ornamental design for a table lamp, substantially as shown.
